[57] CLAIM

The ornamental design for a hair curling iron or the like, as shown and described.

DESCRIPTION

FIG. 1 is a top plan view, the bottom plan view being the mirror image thereof, of a hair curling iron or the like showing our new design;

FIG. 2 is a left side elevational view thereof;

FIG. 3 is a right side elevational view thereof;
 FIG. 4 is a bottom plan view, showing the open position;

FIG. 5 is a front elevational view thereof;

FIG. 6 is a rear elevational view thereof; and

FIG. 7 is a perspective view thereof.
